DENTAL APPARATUS

Rudolph Klicka, Pittsburgh, Pa.

Application August 8, 1933, Serial No. 684,182

3 Claims. (Cl. 32—19)

My invention relates to dentistry, and consists in instrumentalities for and method of obtaining the true "bite" for the construction of artificial teeth.

- 5 In the accompanying drawing Fig. I is a view in side elevation of dental instruments embodying the invention; in this view the mandible of the patient is indicated in full lines, and his face in dotted lines. Fig. II is a view of an 10 upper dental tray, comprising one element of my set of instruments, and Fig. III is a cross-sectional view of the same, taken on the plane III—III of Fig. II. Fig. IV is a view in plan from above of the lower dental tray of the set. 15 Fig. V is an isometric view of a buccal spoon, two of which are included in each set of my instruments. Fig. VI is a view in plan from below of the upper dental tray, showing on its surface a typical record of the movements of 20 a patient's mandible. And Fig. VII is a cross-sectional view, to larger scale, taken on the plane VII—VII of Fig. I.
- The set of dental instruments comprises an upper tray 1 which is shaped in general as 25 shown in Figs. II and III. The tray comprises a portion 1a, adapted to receive a mound M of wax compound or such other molding compound as is generally used to take a direct impression of a patient's mouth, and a portion 1b adapted 30 in service to extend from the mouth of the patient. The two portions 1a, 1b conveniently extend in common plane, and, advantageously the side edges of the tray are turned upward, to provide flanges 1c. The portion 1a of the 35 tray is provided with a plurality of orifices 1d, in which the molding compound is adapted to nest (Fig. VII); the orifices 1d and flanges 1c serve to secure the molding compound in place. The tray 1 is formed of sheet steel, and is 40 coated with baked white enamel. The nether surface of portion 1b is treated with muriatic acid, to remove the glaze from the enamel, whereby it becomes a surface upon which pencil lines may be recorded and clearly visible.
- 45 A lower tray 2 is provided for cooperation with tray 1. Tray 2 is fashioned of sheet stainless steel; it comprises an inverted channel having walls 2a, 2b, 2c shaped in plan as the teeth of the lower jaw are aligned, and the channel is 50 adapted to be charged with molding compound N. The inner wall 2c of the channel is continuous with the horizontal wall 2b, while the outer wall 2a thereof is interrupted at the points 2d. A downward extending tongue 2e is formed 55 as an integral continuation of the wall 2b, and such tongue is windowed to admit of the formation of a flange 2f which serves at the front of the tray as the wall 2a serves along the outer sides thereof to confine the molding compound N. A pencil clip 3 is secured in any convenient manner upon the front face of tongue 2e, and in this clip a pencil 4 is held, the pencil being positioned with its point directed upward, as indicated in Fig. I. An important feature of the tray 2 is found in the member 2h which, 10 formed integrally with the tray, arches upward from the lower edge of the wall 2c. The member 2h serves as a seat for a mound P of molding compound or other suitable material, not necessarily molding compound, which is yielding and yet adapted to provide a substantial support for holding the two trays 1, 2 in proper spaced-apart relation. An orifice 2k is formed in the arched member 2h, to assist in securing the mound P in place.
- 15 Two buccal spoons of the structure shown in Fig. V are provided. As will presently appear in greater detail these spoons are adapted to hold a charge of plaster in position in the patient's mouth on opposite sides of the trays 1, 2. Each spoon 5 comprises a body portion 5a having flanges 5b formed along its sides; an extension 5c serves as a handle for the dentist using the spoon; and the whole spoon structure is formed of sheet stainless steel, and is formed 20 in such shape as to configure comfortably to the cheeks of the patient.
- 25 According to usual practice, I charge the trays 1 and 2 with molding compound. Additionally, I place a mound P of molding compound or other suitable material in the recess provided between the flange 2c and member 2h of the lower tray. Then, I position the trays in the patient's mouth, and press them into place over 30 his gums (or teeth), as indicated in Fig. I.
- 35 The manner in which this is accomplished will be well understood in the art, and requires no elaboration herein. It is characteristic of my structure, however, that the lower lip of the patient lies between the tongue 2e and flange 2b of the lower tray, and that a mound P is 40 organized between the plates or trays. The mound P extends upward into engagement with the bottom of tray 1, serving to hold the two trays 1, 2 in proper spaced-apart relation, which 45 relation, of course, depends in each case upon the structure of the patient's mouth and jaw. When this relation has been determined, by having the patient place the condyles of his 50 mandible in their normal seated positions, the 55

pencil 4 is adjusted in clip 3, so that its point rests against the recording surface on the bottom surface of tray 1. Then, I cause the patient to move his mandible backward and forward 5 between straight protrusive and retrusive positions, the mound P riding against the nether face of the tray 1. Thus, I obtain on the recording surface a visible line 6, cf. Fig. VI.

Next, I instruct the patient to move his mandible to and fro between left lateral protrusive and retrusive positions in such manner that a line 7 is scribed upon the recording surface of tray 1. Then a similar oscillation of the mandible to the right is effected, and a line 8 is recorded. It will be observed that in this manner 10 I obtain a plurality of substantially linear lines on the recording surface of tray 1; due to the spacer mound P the oscillations of the mandible are effected in a substantially horizontal plane, 15 or a single plane; the several directions of oscillation or reciprocation of the mandible extend angularly one to the other, and the recorded lines thereof meet at a point 9 of intersection. The point 9 is a perfect center, or point of reference, 20 to be used in the construction of a plate of artificial teeth—the point 9 visibly indicates the true bite of the patient's jaws.

When the point 9 has been obtained, I fill the two buccal spoons 5 with plaster 10 (or other 30 suitable material), and insert them in the patient's mouth, along the opposite sides of the trays 1, 2. I so adjust the patient's jaws that the pencil is directed immediately to the visible reference point 9, and I instruct the patient to 35 bite hard, bringing pressure to bear upon the mound P of compression or molding compound. This biting pressure reacts to force the patient's condyles upward into seated positions and brings his mandible into desired position of vertical 40 adjustment, while by means of point 9 proper horizontal registration of the jaws is obtained. With the mandible maintained in such position the plaster 10 is hardened along the opposite edges and between the registered trays 1, 2, as 45 indicated in Fig. VII. Accordingly, the molding units M and N, conforming to the upper and lower impressions U and L of the patient's mouth, are temporarily integrated in proper registration. The integrated structure is then 50 removed from the mouth, and the construction of the artificial teeth may be accomplished in manner well understood in the art. The provision of the visible point 9 of reference—indicative of the true bite of the patient—is so far as 55 I know the most accurate and effective method of reproducing a patient's bite in the usual articulating frame (not shown).

I may remark that the tray 2 shown in the drawing is the tray employed when the patient 60 has had his lower set of teeth removed. However, if his lower set of teeth have not been removed, and he is to obtain only an upper set of artificial teeth, I provide a lower tray which is substantially of the same construction as the tray 2, but is relatively larger, to accomodate the natural teeth in the mandible.

It will be understood, therefore, that my invention permits the practice of the above-described technique in cases where only one set 70 of artificial teeth (lower or upper) is to be pro-

vided in a mouth which still retains one sound set (upper or lower) of natural teeth.

I claim as my invention:

1. The method of obtaining "bite" for the construction of artificial teeth, which method comprises severally fitting two rigid trays including impression compound to the upper and lower jaws of the patient, causing the patient to close his jaws and force said trays against compressible spacing means, and thereby automatically 10 spacing said trays vertically in substantially fixed relative positions relational to the normal or natural spacing of the patient's jaws, recording the movements of the lower jaw between central and lateral protrusive and retrusive positions, and thereby obtaining a visible point of reference, maintaining the jaws of the patient in horizontal registry by reference to said point, and, by causing the patient "to bite" hard against said spacing means, forcing his condyles 15 upward into seated positions, and, while maintaining such relation of the jaws, casting and hardening a mass of binder along each of the opposite sides of and between said trays.

2. The method of obtaining "bite" for the construction of artificial teeth, which method comprises fitting a rigid tray including impression compound to each of the upper and lower jaws of the patient, causing the patient to close his jaws and force said trays against a compressible spacing mass, and thereby automatically 30 spacing the trays vertically in substantially fixed relative positions relational to the normal or natural spacing of the patient's jaws, recording the movements of the lower jaw relatively to the upper and thereby obtaining a visible point of reference, maintaining the jaws of the patient in horizontal registry by reference to said point, and, by causing the patient to close his 35 jaws and exert compression upon said spacing mass, forcing his condyles upward into seated positions, and, while maintaining such relation of the jaws, casting and hardening a mass of binder along each of the opposite sides of and between said trays.

3. The method of obtaining "bite" for the construction of artificial teeth, which method comprises fitting a rigid tray including impression compound to each of the upper and lower jaws of the patient, causing the patient to close his jaws and force said trays against a compressible supporting mass, and thereby automatically 50 spacing the trays vertically in substantially fixed relative positions relational to the normal or natural spacing of the patient's jaws, recording the movements of the lower jaw relatively to the upper and thereby obtaining a visible point of reference, maintaining the jaws of the patient in horizontal registry by reference to said point, and, by causing the patient to close 55 his jaws and exert compression upon said supporting mass, forcing his condyles upward into seated positions, and, while maintaining such relation of the jaws, casting and hardening a mass of binder in a buccal spoon along each of the opposite sides of said trays, and thereupon removing as a unit the so integrated trays, spoons, and binder from the mouth of the patient.

RUDOLPH KLICKA.
